UNITED STATES PATENT OFFICE.

MORRIS P. BRAY, OF NEW HAVEN, CONNECTICUT.

BACK-PROTECTOR FOR CORSETS.

SPECIFICATION forming part of Letters Patent No. 268,994, dated December 12, 1882.

Application filed November 4, 1882. (No model.)

To all whom it may concern:

Be it known that I, MORRIS P. BRAY, of New Haven, in the county of New Haven and State of Connecticut, have invented new Im-
5 provements in Back-Protectors for Corsets; and I do hereby declare the following, when taken in connection with accompanying drawings and the letters of reference marked thereon, to be a full, clear, and exact description of 10 the same, and which said drawings constitute part of this specification, and represent, in—

Figure 1, a rear view showing the pad as applied to the corset; Fig. 2, a vertical central section of the pad on line α α of Fig. 1; Fig. 15 3, the surface of the pad, showing the loops; Fig. 4, a transverse section through the pad and back sections of the corset.

This invention relates to an improvement in corsets, the object of the invention being to 20 provide a protector at the back which will cover the lacing and lie between the lacing and the back of the wearer, yet easily adjustable, and so as not to interfere with the lacing of the corset; and the invention consists in a strip or 25 pad having loops vertically on its outer surface, through which the runs of the lacing are passed, the portion of the pad each side the loop passing beneath the respective edges of the back of the corset, as more fully hereinaf- 30 ter described.

A represents the back or lacing section of one part of the corset, and B the corresponding section of the other part, each provided with eyelets for lacing, in the usual manner.

C is a pad, a little wider than the space intended to be left between the two edges of the corset when laced, made entirely independent of the parts of the corset. It is best made from two or more thicknesses of material, as seen 35 in Fig. 4, with several stays, a , introduced therein, and in the manner of making sections 40 of corsets. On the outside, and preferably in its vertical central line, several loops, b , are attached. These loops are best attached by 45 taking a strip of tape or double fabric and

stitching it to the pad at different points, as indicated in Figs. 2 and 3, the loops corresponding to the cross of the lacings in the corset. The pad is applied upon the inside of the corset, so as to bring the loops on the outside 50 and between the two edges. The lacing is then introduced in the usual manner, the runs of the lacing passed through more or less of the loops. Then, when the corset is completely laced, the pad is secured in its proper position 55 in the corset, and serves as a protector upon the inside of the corset, and also serves as an additional back-stay.

If the wearer desires to cover the lacing upon the outside, so as to prevent its appearance 60 through the dress, then the stay may be placed upon the outside of the corset, with the loops inward between the two parts.

This construction enables me to produce a back pad or protector for corsets, which may 65 be sold as an article in the market entirely independent of the corset, and which any wearer may apply to the corset at pleasure; or, if at any time it is not required, it may be readily removed. It necessitates no change in the 70 construction of the corset, and hence is universal in its adaptation.

I prefer to make the pad with several stays, both for the purpose of keeping the pad in its position and also to serve as an additional or 75 auxiliary back-stay; but it may be simply a pad used as a protector or cover for the lacings.

I claim—

The herein-described back-pad for attachment to corsets, consisting of the pad C, constructed with loops on its surface through which the lacings pass, the said pad constructed to extend each side of the loops over the eyelet-sections of the corset, substantially as 80 described.

MORRIS P. BRAY.
